MULTIPLE STRAND THERMAL PULL WIRE
UNIT

Philip Sitzer, Irvington, N. J., assignor to Tung-Sol Electric Inc., Newark, N. J., a corporation of Delaware

Continuation of application Serial No. 573,736, January 20, 1945. This application September 19, 1949, Serial No. 116,597

1 Claim. (Cl. 297—12)

1

This invention relates to vane type thermal switches of the type controlled by the expansion and contraction of a pull wire element.

One object of the invention is a new and improved vane type thermal switch characterized by its dependability, uniformity of operating characteristics over long periods of time, and the uniformity of operating characteristics of the devices when produced in quantity.

Another object of the invention is a new and improved vane type switch of the above character wherein a large uniform operating force is applied to the vane and wherein uniform operating characteristics over long periods of time and uniformity of operating characteristics of switches produced in quantity are obtained.

Another object of the invention is a new and improved vane type thermal switch characterized by its simplicity of structure.

Still another object is a new improved vane type thermal switch.

For a better understanding of the invention reference may be had to the accompanying drawings, of which—

Fig. 1 is a side view of the multiple pull wire of a thermal switch embodying the invention;

Fig. 2 is a view taken at right angles to Fig. 1 and as viewed from the left;

Fig. 3 is a fragmentary view on an enlarged scale showing the supporting means for the multiple pull wire of the switch of Fig. 1;

Fig. 4 is a perspective view of the thermal switch of Figs. 1 and 2 mounted in an envelope;

Fig. 5 is a side view of another embodiment of the invention;

Fig. 6 is a view thereof at right angles to Fig. 5;

Fig. 7 is a perspective view of this embodiment housed in a casing;

Fig. 8 is a view illustrating one step in the method of forming and mounting the multiple strand wire unit of the embodiment of Figs. 5 to 7;

Fig. 9 illustrates another step;

Fig. 10 illustrates another step;

Fig. 10a is a sectional view through the assembly of Fig. 10;

Fig. 11 illustrates another step in the method;

Fig. 12 illustrates a further step in the method;

Fig. 13 is a view of a detail of the multiple strand unit of Figs. 5 to 7; and

Fig. 14 is a perspective view of a detail of the mount of Figs. 5 to 7.

In Figs. 1 to 4 I have illustrated one embodiment of my new and improved switch structure

2

having in combination a snap action vane type switch actuator and a multi-strand thermal pull wire wherein the stress on each strand is equalized to provide more dependable positive operation and more uniform characteristics throughout its life. More particularly the switch comprises a sprung vane 2 secured at its ends to a frame member 4 and carrying a contact 6, a fixed contact 8 engageable by the contact 6 in one position of the vane 2 and a coil 10 of expansible wire, the contraction and expansion of which control movement of the vane to and from contact closing position.

In accordance with this embodiment of the invention the coil 10 is supported at its ends by members 12 of insulating material about which the wire is wound under tension so as to provide a plurality of strands extending between the members with the strands being uniformly tensioned at all times. In the particular embodiment shown these members 12 are tubular in shape. The members 12 are mounted on bars or rods 14 which pass therethrough. The ends of these rods are secured to the arms of V or U-shaped yoke members 16. The upper yoke member 16 hangs on one arm of a right angle bracket 18, the other arm of which is secured to the vane 2, the bracket being provided with a U-shaped section 20 for reception of the yoke member. The central stretch of the lower yoke member 16 passes under one arm of a bracket 22, the other arm of which is secured to one end of vane 2 where it is attached to the frame 4, the bracket 22 being provided with an inverted U-shaped section 23 for reception of the yoke member.

With this structure I eliminate all mechanically operated levers and knife-edge pivots that restrict movement to one plane and thereby enable the several switch elements to cooperate to provide greatly improved operation and with uniform stress on the several strands.

The wire forming the coil 10 is preferably suitably insulated as by an enamel coating and the number of turns and the diameter of the wire are such that the coil has a relatively high resistance. As one example, when enameled Nichrome wire of .0008" diameter is used to form the coil 10 and a sufficient number of turns provided, the power absorbed by the coil is less than 150 milliwatts. The stretches of the coil 10 are preferably secured to the members 12 by means of cement 24 as shown best in Fig. 3.

With the above described arrangement, the tension of the strands of coil 10, when the wire

forming the same is cold, acting through the upper yoke member and bracket 18 holds the vane 2 in one constrained position. When electric current flows through the coil 10 the wire expands and permits the vane 2 to snap to another position. Because of the particular yoke mounting of the coil, that is, because of the free suspension of the upper yoke member from the bracket 18 and similar coupling between the lower yoke member and bracket 22, any unequal pull of a wire or wires on one end of a spool 12 tends to shift the yoke or yokes about the suspension points so as to equalize the pull of all the wires. Thus there will be a balanced distribution of the tension among the various strands of the coil, with resultant improved operation of the switch.

As shown in Fig. 4, the frame 4 may be mounted on an insulating disk 26 of glass or the like, forming a closure for a glass vessel 28 enclosing the switch elements. Electrical terminals 30 on the under side of the disk, suitably connected with the ends of the coil 10, with the fixed contact 8 and with the frame 4, provide means for connecting the thermal switch into the circuit it is to control. The frame 4 is mounted on support wires 32 one of which serves as the electrical connection to one terminal 30. The fixed contact 8 is carried on the end of a wire 34 which is insulatedly mounted on the frame 4 by means of a bead 36 fused about the wire and secured to a strip 38 carried by the frame, the other end of the wire 34 being connected to a terminal 30.

In the embodiment of Figs. 5, 6 and 7 the multiple strand pull wire is formed of a unit 40 with the ends or turns of the multiple-wire coils firmly mounted in beads 41 and 42. These beads are identical in construction and bead 41 is mounted in an eyelet 43 (see Fig. 14) formed in a bracket arm 44 extending generally transversely to the constrained vane 2 and having a part 44' turned at right angles to the bracket and fastened as by welding to the vane 2. The eyelet 43 is formed around its edge with a curved seat 43' for the reception of the bead 41. The end of the bracket arm 44 is provided with a slot 45 extending from the eyelet 43 outward, which permits assembly of the bead within the eyelet 43 by passing the multiple strand wire through this slot 45. The bead 42 at the other end of the multiple strand unit is mounted in a bracket 46 which is identical with the bracket 44 in which the bead 41 is mounted but in this case the flange 46' of the bracket 46 is fastened as by welding to the frame 4'. The switch shown in Figs. 5 and 6 may be mounted in an envelope indicated at 28 having four terminals 47, 48, 49 and 50 with the terminals 47 and 48 leading to the multiple strand unit 40. The terminal 49 leads to the frame 4' and the terminal 50 leads to the support 8' for the fixed contact 8. In the particular embodiment shown in Fig. 5 the contact-actuating arm 8' is insulatedly carried by a U-bracket 51 fastened to the frame 4' with a connecting wire 52 leading from the contact carrier 8' to the lead-in wire 50. Also in the particular embodiment shown, the frame 4' is carried by a pair of support wires 53 embedded in the end of the envelope, one of these wires 53 leading to the terminal 49.

The multiple strand pull wire may be coiled and mounted in the beads 41 and 42 in any suitable manner but in Figs. 8 to 12 I have illustrated a new and improved method for accomplishing this purpose. The first step (Fig. 8) consists in coiling the wire 60 about a pair of spaced

very small diameter mandrels 61 with the turns 60' of the wire evenly placed and adjacent each other. Preferably the wire 60 is provided with an enamel or other insulating coating so that even though they may touch they are insulated against short circuit by this insulation from the comparatively small voltage difference between the turns. With the wire 60 thus wound tightly about the spaced mandrels 61 the multiple strands are formed in co-planar layers 62 spaced from each other a distance equal to the diameter of the mandrels 61 (Fig. 8(a) and (b)). The next step in the formation of the unit is shown in Fig. 9. This step consists in gathering the main body of the multiple wires 62 rather closely together and then embedding or encasing the gathered together multiple wires or turns 62 in wax or any other readily removable material for temporarily holding the multiple strand wire in assembled relation while mounting. This readily removable encasing material in which the multiple strand wire is embedded is indicated at 63 and it preferably extends to a point not very far removed from the mandrel 61 at both ends so as to leave uncased parts 62' at the ends of the multiple strand assembly. Thus the multiple strand assembly is held firmly in the assembly unit with the strands of wire parallel to each other and closely grouped whereby the pull of the group approaches that of a single pull wire. Fig. 9 roughly illustrates the close grouping of the wires 62 in the temporary casing 63. The mandrels 61 are removed, leaving the assembled unit as illustrated in Fig. 10. The next step is illustrated in Fig. 11 and this consists in assembling over the ends 62' of the coiled multiple strand wire hollow glass beads 65 which are in the form of cups as shown in detail in Fig. 13, each with a small hole 66 formed in the bottom of the cup, the open top of the cup being shown at 61. The exposed ends 62' of the multiple wire strand assembly are inserted through these small openings 66 with the open sides of the cup-shaped beads 65 disposed outwardly of the assembly, the ends of the multiple strand coil assemblies extending through the ends of the cup-shaped beads 65 to a point where the end surfaces of the coil turns are approximately or nearly approximately even with the open side or ends of the beads. These beads 65 are preferably of glass but they may be of any other suitable material. The next step consists in anchoring the ends 62' of the multiple strand coil assembly to the hollow glass beads 65. This step is illustrated in Fig. 12 and consists in filling each of the hollow beads 65 with a suitable cement 68, care being taken that each end of the coil is covered with and embedded in the cement. The cement may be any suitable cement which upon hardening firmly anchors the ends 62' of the multiple strand assembly to the glass beads. This cement is preferably of insulating material. After the cement has been properly dried the wax casing 63 in which the main body of the wire assembly is embedded can then be dissolved or melted off so as to leave the multiple strand closely assembled wire strands 62 exposed all the way between the glass beads 65. Fig. 5 shows the wax casing 63 thus removed and the structure at the ends are indicated at 41 and 42. As above described the unit thus formed may be placed in the flasher or relay which has suitable eyelet supports. As shown in Figs. 5, 6 and 7 illustrating a thermal switch of the sprung vane type the rounded surfaces 65' of the beads rest upon the seats 43' formed

around the eyelets. The beads 65 may also be formed of an insulating material and molded in place about the ends 62' of the wires 62.

A thermal switch is thus obtained having multiple pull coils of fine wire which simulates very closely a single pull wire, with all strands of the parallel turns of wire assembled closely adjacent a central point. The creation of uneven pull among the individual wires when the unit is adjusted or when it is operating is thus largely obviated and for practical purposes the pull is substantially uniform on all strands of the wire. As above indicated the relay may be used in either hot wire flashers or relays.

No particular circuit has been illustrated in the drawings as circuits suitable for control by thermal switches of the general type herein described are well known and form no part of the present invention.

From the above description it will be apparent that the invention provides an improved mount for the multiple wire coil of a thermal switch that insures uniform balanced pull of the various strands of the coil.

In both the modification of Figs. 1 to 4 and the modification of Figs. 5 to 14 the pull of the multiple strands collectively and individually is exerted substantially at a common point, in the first modification at the hooks 20 and 23 of the brackets 18 and 22 and in the second modification at the eyelet 43, with the members 18 and 44 functioning as the means for transmitting the pull of the multiple wire unit directly to the movable contact and with the small mandrel 12 and yoke mount and the beads 41, 42 being directly attached to the multiple wire assembly for transmitting the pull to the members 18 and 44.

Particularly good results have been obtained with my new and improved multi-strand structures in combination with the vane type switch illustrated in the drawings as they cooperate to

insure precise, positive and dependable switch operation throughout the switch life. Moreover, with this new and improved structure I have eliminated all mechanical levers and knife-edge pivots and use in effect as the only moving part a buckling vane which together with the improved multi-strand structure provides in addition to a simple, dependable unit one that can be readily produced in quantity at low cost.

Furthermore, my improved pull wire mounting and method also effects further reduction in manufacturing costs and enables substantially uniform stress to be placed on each end.

This is a continuation of my application Serial No. 573,736, filed January 20, 1945, now abandoned.

I claim:

A multiple pull wire unit for mounting in a thermal switch comprising multiple turns of fine wire closely disposed to each other with the opposite ends of the multiple strand unit disposed in insulating cup-like shells having a hemispherical bottom part including a central opening therein, with the wires passing through said opening and a cement-like filler in the shell in which the ends of the wires are embedded.

PHILIP SITZER.
